VOLTAGE REGULATORS

Bert K. Naster, 3000 Taft Road, Hollywood 4, Fla.
Filed Dec. 21, 1959, Ser. No. 860,909
9 Claims. (Cl. 323—45)

This invention relates to new and improved voltage regulators adapted to supply a substantially constant output voltage, despite rather wide variations in the input voltage.

One object of the present invention is to provide new and improved voltage regulators of the electromagnetic or transformer type, adapted to supply a substantially constant voltage from an alternating current supply which is subject to wide voltage variation.

Another object is to provide a new and improved voltage regulator of the foregoing character which is so arranged that the regulator will not be overloaded, and will not draw excessive current or power, if the output terminals of the regulator are accidentally short-circuited.

A further object is to provide a new and improved voltage regulator which has no moving parts, but employs only rugged transformer and capacitor units, so that the regulator will be inexpensive to manufacture, yet will give dependable service for an indefinite time.

Further objects and advantages of the present invention will appear from the following description, taken with the accompanying drawings, in which:

FIG. 1 is a schematic wiring diagram showing the circuit arrangement of a voltage regulator to be described as one illustrative embodiment of the present invention.

FIG. 2 is a diagrammatic view showing the layout and connections of the transformer and capacitor units employed in the regulator.

FIG. 3 is a plan view of the main transformer unit of the regulator shown in FIGS. 1 and 2.

FIG. 4 is a sectional view, taken generally along a line 4—4 in FIG. 3.

FIG. 5 is a diagram showing the wave forms of the input and output voltages of the regulator.

FIGS. 6, 7 and 8 are views similar to FIGS. 1, 2 and 3 respectively, but showing a modified voltage regulator.

As already indicated, FIGS. 1—5 illustrate a voltage regulator 10, adapted to supply a substantially constant output voltage across a pair of output terminals 12 and 14, even though the input voltage to the regulator may vary over a rather wide range. As shown, the alternating input voltage may be applied across a pair of input terminals 16 and 18. The input voltage may be derived from an ordinary household power line, or any other source of alternating current, which may be at any suitable voltage and frequency, such as a nominal voltage of 110 volts and a frequency of 60 cycles. The output voltage will not change to any substantial extent even though the input voltage may vary over a considerable range, such as from 80 to 140 volts, for example. The output may be at any suitable voltage, such as 120 volts, for example.

The illustrative voltage regulator 10 comprises two transformer units 20 and 22, and a capacitor 24. The first transformer unit comprises a primary winding P1 and two secondary windings S1 and S2. The second transformer unit 22 has a primary winding P2 and a secondary winding S3.

2

The windings P1, S1 and S2 of the first transformer 20 are mounted on a lamination or core 26. It is preferred to provide magnetic shunts 28 and 30 between the windings. Thus, the shunt 28 is between the primary P1 and the secondary S1, while the shunt 30 is between the secondaries S1 and S2.

Similarly, the windings P2 and S3 of the second transformer 22 are mounted on a lamination or core 32. It is preferred to provide a magnetic shunt 34 between the windings P2 and S3. In each case, the magnetic shunts decouple the windings and increase their leakage reactances.

One end of the first primary winding P1 is connected to the input terminal 16 by a lead 36. The other input terminal 18 is connected to the output terminal 14 by lead 38. A lead 40 extends between the other output terminal 12 and one end of the secondary winding S3.

In the illustrated arrangement, all of the windings P1, S1 and S2 are connected in a closed series circuit or loop, which also includes the capacitor 24. Thus, the transformer 20 is connected as an autotransformer. Starting from the lead 36, this series circuit comprises the primary winding P1, a lead 42, the secondary winding S1, a lead 44, the secondary winding S2, and the capacitor 24. This loop tends to act as a resonant circuit in which the negative reactance of the capacitor 24 tends to neutralize the positive leakage reactances of the windings P1, S1 and S2. The extent to which the circuit is resonant varies with the input voltage. This shifting in the resonant condition contributes to the overall regulating action of the regulator.

In the case of the second transformer 22, the windings P2 and S3 are connected in series across the output terminals 12 and 14. A lead 48 extends between the windings P2 and S3. Thus, the second transformer 22 is also connected as an autotransformer.

The circuits of the transformers 20 and 22 are interconnected by means of a lead 50 which extends between the junction leads 42 and 48. It will be seen that the lead 50 has the effect of connecting the primary windings P1 and P2 in series across the input terminals 16 and 18. Thus, the input voltage is divided between the primaries P1 and P2, but this effect is modified by the presence of the secondaries S1 and S2 and the capacitor 24 in series with P1. The shift of the resonant condition in the circuit of the transformer 20 varies the division of the voltage in such a manner as to give a regulated output voltage.

FIGS. 3 and 4 illustrate various details of the first transformer 20. As shown, the lamination or core 26 comprises an elongated central leg 54, on which the windings P1, S1 and S2 are mounted. The lamination 26 has a generally rectangular outer member 56, comprising a pair of relatively short end legs 58 and 60, which extend between the ends of relatively long side legs 62 and 64. The central leg 54 extends between end legs 58 and 60, so that the outer member 56 will provide a return path for the magnetic flux generated by the windings P1, S1 and S2.

It is preferred to employ high reluctance, saturable joints 68 and 70 between the central leg 54 and the end legs 58 and 60. Thus, the left hand end of the central leg 54 engages the end leg 58 only along two small diagonal corner faces 72 and 74. The remainder of the left hand end of the central leg 54 is separated from the end leg 58 by a non-magnetic gap 76, which may be filled with fiber

or other suitable material to minimize vibration. At the right hand end of the lamination 26, the central leg 54 has a small nose portion or projection 78, which is the only part of the central leg which actually engages the end leg 60. Elsewhere, the central leg 54 is separated from the end leg 60 by non-magnetic gaps 80 and 82, which again may be filled with fiber or some other suitable material. The joints 68 and 70 increase the leakage reactances of the windings P1, S1 and S2. Since the magnetic flux is concentrated in the joint elements 72, 74 and 78, they saturate rather readily as the flux increases. The saturation of the joints causes a further increase in the leakage reactances of the windings.

In the illustrated construction, the magnetic shunts 28 and 30 take the form of projections on the side legs 62 and 64. These projections are located between the coils P1, S2 and S2. It will be seen that the projections are formed integrally on the side legs 62 and 64. The projections extend inwardly so that they are separated from the central leg 54 by narrow gaps 86 and 88.

The second lamination 32 is very similar in construction to the first lamination 26. Thus, the lamination 32 comprises a central leg 90 which extends between the ends of a rectangular outer member 92. The magnetic shunts 34 take the form of projections extending inwardly toward the central member 90, from the outer member 92. High reluctance saturable joints 94 and 96 are preferably provided between the central leg 90 and the outer member 92.

The various coils may be wound with different numbers of turns in order to provide various output voltages and regulation characteristics. However, it is thought that the following coil data, for a particular regulator which has been successfully used, will be of interest:

Winding	No. of Turns	Size of Wire
P1	350	No. 20
S1	250	No. 18
S2	335	No. 18
P2	230	No. 18
S3	125	No. 20

In this regulator, the capacitor 24 had a value of 15 microfarads.

For one set of operating conditions, the voltages across the various coils were as follows:

	Volts
P1	154
S1	106
S2	186
P2	91
S3	37
Capacitor	438
Input	118
Output	121.5

These conditions existed with an output load of 224 watts and a power input of 300 watts.

FIG. 5 illustrates the wave forms of the input and output voltages and clearly shows the phase relation between these voltages.

In FIG. 1, the wave forms of the voltages across the various coils are shown by oscillograms adjacent the coils. An additional oscillogram, adjacent the capacitor 24, shows the wave form of the voltage across the capacitor.

The illustrated voltage regulator 10 maintains the output voltage substantially constant over a wide range of input voltage. This may be illustrated by the following typical regulation chart:

Input, Volts.....	80	90	100	110	120	130	140
Output, Volts.....	118.5	120.5	121.0	121.0	120.5	119.5	118.5

In this example, the variation in the output voltage is

only one and one-half volts, while the input voltage varies over a range of sixty volts.

If the output terminals 12 and 14 are accidentally short-circuited, the high leakage reactance of the secondary winding S3 limits the output current so that no damage is done to the regulator. Moreover, the short-circuit of the output throws the regulator out of resonance so that the regulator does not draw excessive current or power. As soon as the short-circuit is removed, the regulator delivers normal output voltages. There is no need for fuses or other protective devices.

FIGS. 6 through 8 illustrate a modified regulator 110, which is very much the same as the regulator 10 except that the secondaries S1 and S2 are combined into a single winding S4. The primary P1 is replaced by a winding P1a having a series of taps 112 at its right hand end so that the output voltage may be varied. Similarly, the secondary S3 is replaced with a winding S3a having a series of taps 114 at its left hand end.

Instead of being connected directly to the right hand end of the primary winding P1a, the right hand end of the secondary S3a is connected to a switch member 116 which may be engaged with any of the taps 112. The output lead 40 is connected to a switch member 118 which may be moved into engagement with any of the taps 114.

As before, the windings P1a and S4 are connected in series with the capacitor 24 to form a circuit or loop which is resonated to varying degrees by the capacitor, according to the current in the circuit. The primary windings P1a and P2 are connected in series across the input terminals 16 and 18 as above.

As shown in FIGS. 7 and 8 the secondary S4 occupies the space formerly occupied by the secondaries S1 and S2, while the primary P1a replaces the primary P1. The magnetic shunts 30 are eliminated to form a slightly modified lamination 26a. Otherwise, the lamination is the same as in FIGS. 3 and 4. The lamination 32 remains the same as in FIG. 2.

The operation of the voltage regulator 110 is much the same as the operation of the regulator 10, except that the switches 116 and 118 make it possible to adjust the regulated output voltage over a considerable range. It will be understood that the control switches could easily be incorporated into the regulator 10 of FIGS. 1 and 2.

The illustrated regulators provide truly remarkable voltage regulation, despite the fact that the regulators have no moving parts and are made up of simple transformer and capacitor units. It will be apparent that the regulators are highly dependable, yet very inexpensive.

Various other modifications, alternative constructions and equivalents may be employed without departing from the true spirit and scope of the invention, as exemplified in the foregoing description and defined in the following claims.

I claim:

1. In a voltage regulator, the combination comprising a first transformer having a first primary winding and first and second secondary windings, a second transformer having a second primary winding and a secondary winding, a pair of input terminals for receiving alternating current, means connecting said first and second primary windings in series across said terminals, a pair of output terminals for delivering alternating current, means connecting said secondary primary winding and said secondary winding of said second transformer in series across said output terminals, a capacitor, and a circuit connecting said capacitor, said first primary winding, and first and second secondary windings in a closed series loop in which said capacitor tends to neutralize the inductive reactances of said first primary winding and said first and second secondary windings.

2. In a voltage regulator, the combination comprising a first transformer having a first primary winding and first and second secondary windings, a second transformer

5

having a second primary winding and a secondary winding, said first transformer having a magnetic core with a first magnetic shunt between said first primary winding and said first secondary winding, said core having a second magnetic shunt between first and second secondary windings, said second transformer having a magnetic core with a magnetic shunt between said second primary winding and said third mentioned secondary winding, a pair of input terminals for receiving alternating current, means connecting said first and second primary windings in series across said terminals, a pair of output terminals for delivering alternating current, means connecting said second primary winding and said secondary winding of said second transformer in series across said output terminals, a capacitor, and a circuit connecting said capacitor, said first primary winding, and first and second secondary windings in a closed series loop in which said capacitor tends to neutralize the inductive reactances of said first primary winding and said first and second secondary windings.

3. In a voltage regulator, the combination comprising a first transformer having a first primary winding and a first secondary winding, a second transformer having a second primary winding and a second secondary winding, a pair of input terminals for receiving alternating current, means connecting said first and second primary windings in series across said input terminals, a pair of output terminals for delivering alternating current, means connecting said second primary winding and said second secondary winding in series across said output terminals, a capacitor, and means connecting said capacitor, said first primary winding and said first secondary winding in series in a closed loop in which said capacitor tends to neutralize the inductive reactances of said first primary winding and said first secondary winding.

4. In a voltage regulator, the combination comprising a first transformer having a magnetic core, a first primary winding and a first secondary winding mounted on said core, said core having a magnetic shunt between said first primary winding and said first secondary winding, a second transformer having a second magnetic core, a second primary winding and a second secondary winding mounted on said second core, said second core having a magnetic shunt between said second primary winding and said second secondary winding, said shunts imparting high leakage reactances to said first and second secondary windings, a pair of input terminals for receiving alternating current, means connecting said first and second primary windings in series across said input terminals, a pair of output terminals for delivering alternating current, means connecting said second primary winding and said second secondary winding in series across said output terminals, a capacitor, and a circuit connecting said capacitor, said first primary winding, and said first secondary winding in series in a closed loop in which said capacitor tends to neutralize the inductive reactances of said first primary winding and said first secondary winding.

5. In a voltage regulator, the combination comprising a first transformer having a first primary winding and a first secondary winding, a second transformer having a second primary winding and a second secondary winding, a pair of input terminals for receiving alternating current, means connecting said first and second primary windings in series across said input terminals, one end of said second primary winding being connected to one end of said first primary winding, said first primary winding having a first series of taps thereon adjacent one end thereof, a first switch for connecting one end of said second secondary winding to any of said taps, a pair of output terminals for delivering alternating current, one of said output terminals being connected to the other end of said second primary winding, said second secondary winding having a second series of taps thereon adjacent the other end thereof, a second switch for connecting the other output terminal to any of said second series of taps, a capacitor,

and a circuit connecting said capacitor, said first primary winding, and said first secondary winding in series in a closed loop.

6. In a voltage regulator, the combination comprising a first transformer having a first primary winding and a first secondary winding, a second transformer having a second primary winding and a second secondary winding, a pair of input terminals for receiving alternating current, means connecting said first and second primary windings in series across said input terminals, said second primary winding being connected to one end of said first primary winding, said first primary winding having a series of taps thereon adjacent one end thereof, a switch for connecting one end of said second secondary winding to any of said taps, a pair of output terminals for delivering alternating current, one of said output terminals being connected to the other end of said second primary winding, means connecting the other output terminal to the other end of said secondary winding, taps, a capacitor, and a circuit connecting said capacitor, said first primary winding, and said first secondary winding in series in a closed loop.

7. In a voltage regulator, the combination comprising a first transformer having a first primary winding and a first secondary winding, a second transformer having a second primary winding and a second secondary winding, a pair of input terminals for receiving alternating current, means connecting said first and second primary windings in series across said input terminals, one end of said second primary winding being connected to one end of said first primary winding, one end of said second secondary winding being connected to said one end of said second primary winding, a pair of output terminals for delivering alternating current, one of said output terminals being connected to the other end of said second primary winding, said second secondary winding having a series of taps thereon adjacent the other end thereof, a second switch for connecting the other output terminals to any of said series of taps, a capacitor, and a circuit connecting said capacitor, said first primary winding, and said first secondary winding in series in a closed loop.

8. In a voltage regulator, the combination comprising a first transformer having a magnetic core, a first primary winding and a first secondary winding mounted on said core, said core having a magnetic shunt between said first primary winding and said first secondary winding, said shunt imparting high leakage reactances to said first secondary winding, a second transformer having a second magnetic core, a second primary winding and a second secondary winding mounted on said second core, a pair of input terminals for receiving alternating current, means connecting said first and second primary windings in series across said input terminals, a pair of output terminals for delivering alternating current, means connecting said second primary winding and said second secondary winding in series across said output terminals, a capacitor, and a circuit connecting said capacitor, said first primary winding, and said first secondary winding in series in a closed loop in which said capacitor tends to neutralize the inductive reactances of said first primary winding and said first secondary winding.

9. In a voltage regulator, the combination comprising a first transformer having a magnetic core, a first primary winding and first and second secondary windings mounted on said core, said core having a magnetic shunt between said first primary winding and said first secondary winding, a second transformer having a second magnetic core, a second primary winding and an additional secondary winding mounted on said second core, said second core having a magnetic shunt between said second primary winding and said additional secondary winding, said shunts imparting high leakage reactances to said secondary windings, a pair of input ter-

minals for receiving alternating current, means connecting said first and second primary windings in series across said input terminals, a pair of output terminals for delivering alternating current, means connecting said second primary winding and said additional secondary winding in series across said output terminals, a capacitor, and a circuit connecting said capacitor, said first primary winding, and said first and second secondary windings in series in a closed loop in which said capac-

itor tends to neutralize the inductive reactances of said first primary winding and said first and second secondary windings.
